(57) **CLAIM**

The ornamental design for a dental instrument sleeve, as shown and described.

DESCRIPTION

FIG. 1 is an isometric view of the dental instrument sleeve of this invention, the element shown in broken lines being environmental structure forming no part of the design;

FIG. 2 is a side elevational view, the side opposite being a mirror image thereof; and,

FIG. 3 is an end view, the end opposite being a mirror image thereof.

1 Claim, 1 Drawing Sheet

FIG. 1

FIG. 2

FIG. 3
